UNITED STATES PATENT OFFICE.

GEORGE WILLIAM DOVER, OF CRANSTON, RHODE ISLAND, ASSIGNOR TO GEORGE W. DOVER, INCORPORATED, OF PROVIDENCE, RHODE ISLAND, A CORPORATION OF RHODE ISLAND.

SAFETY-CATCH FOR BROOCHES AND THE LIKE.

1,292,272.

Specification of Letters Patent.

Patented Jan. 21, 1919.

Application filed September 20, 1918. Serial No. 254,922.

To all whom it may concern:

Be it known that I, GEORGE WILLIAM DOVER, a citizen of the United States, residing at Cranston, in the county of Providence and State of Rhode Island, have invented a new and useful Improvement in Safety-Catches for Brooches and the like, of which the following is a specification.

In the usual construction of safety catches for brooches and similar articles of jewelry, the parts of the catch are first assembled into a complete operative device, before soldering, and the keeper or relatively stationary member is then soldered to the brooch or similar article of jewelry. The movable or locking member of the catch, which is necessarily small and delicate, must be strong and rigid to hold its shape and to operate properly, when in use. The heat generated in soldering on the completed catch anneals, weakens or distorts the locking member of the catch, thereby causing the catch to work improperly and in some cases ruining the utility of the catch.

The object of my invention is to produce such a safety catch in two separate parts, whereby the keeper or relatively stationary member is first soldered to the article and the locking member then operatively secured in place by clamping the sides of the keeper together over the locking member.

A further object of my invention is to improve the construction of such a safety catch, thereby improving the operation, forming a more positive lock, prolonging the life and reducing the cost of the catch.

My invention consists in the peculiar and novel construction of a safety catch for brooches and the like, said safety catch having details of construction, as will be more fully set forth hereinafter and claimed.

Figure 1 is an end view of a brooch provided with my improved safety catch with the catch in the open position in full lines and in the closed position in broken lines.

Fig. 2 is a sectional view of the safety catch end of the brooch taken on line 2.2 of Fig. 1 with the catch in the closed or locked position.

Fig. 3 is an inside plan view of the blank from which the keeper or relatively stationary part of the catch is formed.

Fig. 4 is a sectional view through the blank taken on line 4.4 of Fig. 3.

Fig. 5 is a side view of the locking member. 55

Fig. 6 is an edge view of the locking member, and

Fig. 7 is a sectional view showing the locking member inserted in the bent up keeper 60 in the position for movably securing the locking member in the keeper by clamping the sides of the keeper together.

All of the figures in the drawing are enlarged to more clearly show my invention. 65

In the drawing 8 indicates the body of a brooch or similar article of jewelry, 9 a pin-tongue and 10 my improved safety catch which consists when completed, of a relatively stationary keeper 11 and a movable 70 spring locking member 12. The keeper 11 is first struck out in blank form and shaped to have a base portion 13 and circular side portions 14.14 in each of which is a coinciding central pin-tongue opening 15, a radial entrance and egress opening 16, an annular groove 17 semi-circular in cross section and flattened portions 18.18 which when the sides are closed forms a curved slit 19 between the sides, as shown in Fig. 2. The 80 blank is then bent up V shaped, as shown in Fig. 7. The locking member 12 is made of round spring wire circular in form to loosely fit in the bore formed by the annular grooves 17.17, and has the pin notches 20.20 and the 85 flattened operating angular end members 21.21 which extend outward from the locking member through the slit 19 as shown in Figs. 5 and 6 and forms an intermediate 90 wedge shaped opening 22, the narrow inner end 23 of which is slightly less than the diameter of the pin-tongue used.

The bent keeper and locking members are supplied separate to the trade as jewelers' 95 findings. The base portion 13 of the keeper is then soldered to the back of the brooch or similar article, the locking member 12 inserted between the sides of the keeper as shown in Fig. 7, and the sides 14.14 forced together, as shown in Fig. 2, thereby movably securing the locking member in the keeper without annealing and weakening the locking member by the heat generated in soldering the catch on the brooch.

When in use the operating members 21.21 105 form the wedge shaped opening 22 in connection with the entrance opening 16 in the keeper. The end of the pin-tongue 9 passing

through the narrow end 23 of the opening, springs the members 21.21 apart, the loose fit of the locking member in the keeper allowing for this. The locking member is then 5 turned by the operating members 21 into the position as shown in broken lines in Fig. 1, thereby locking the pin-tongue in the catch. The locking member is now held from un- 10 locking or turning in the keeper by the spring of the pin-tongue forcing the end of the pin-tongue into the adjacent notch 20 in the locking member, as shown in Fig. 2. Although the entrance opening in the keeper is shown at the top, it may be on the side if 15 required, in which case the locking member would have a locking movement in one direction.

Having thus described my invention I claim as new:

20 1. A safety catch for brooches and the like, comprising a keeper having a base portion and two circular sides, each side having a coinciding central opening, a radial pin tongue opening, an annular semi-circular 25 groove intersected by the pin tongue opening, the grooves in the sides forming an annular bore, internal reduced portions form-

ing a curved slit between the sides, a circular spring wire locking member in the annular bore and having spring operating members extending outward through the slit in the keeper, said operating members forming 30 a spring wedge shaped opening for a pin tongue.

2. A safety catch for brooches and the like 35 comprising a keeper 11 having a base portion 13, two sides 14.14 in each of which is a coinciding central opening 15, an entrance opening 16, an annular groove 17 and flattened portions 18, the grooves 17.17 forming 40 an annular bore and the flattened portions forming a curved slit 19, a spring wire locking member 12 in the bore formed by the grooves 17.17, and having oppositely disposed pin tongue notches 20.20, and two flattened 45 operating members 21.21 extending outward through the slit 19 in the keeper, the said operating members 21.21 forming a spring wedge shaped opening 22 having a contracted inner end 23, for the purpose as 50 described.

In testimony whereof, I have signed my name to this specification.

GEORGE WILLIAM DOVER.
